UNITED STATES PATENT OFFICE

NORMAN P. HARSHBERGER, OF PASADENA, CALIFORNIA, ASSIGNOR TO BAKELITE
BUILDING PRODUCTS CO. INC., OF NEW YORK, N. Y., A CORPORATION OF DELAWARE

EXPANSION JOINT MEMBER

Application filed April 14, 1930. Serial No. 444,332.

This invention relates to improvements in expansion joint members and method of forming the same.

In the paving of roads, it is common practice to lay the paving material so that it is spaced apart, at frequent intervals, along transverse lines, to permit expansion and contraction of said material when temperature changes occur. It has also been the practice to insert in the transverse spaces flexible expansion joint members, the latter usually consisting of a fabric base which is saturated or coated with a bituminous material. Heretofore, the expansion joint members have been of the "sandwich" type, consisting of several layers of saturated fabric laid edgewise in the spaces between the pavement sections. The main objection to this type of joint resides in the fact that it is open at the upper and lower edges as well as at the ends, and as a result permits oozing of the bituminous material from all edges thereof. This gradual loss of the bituminous material naturally decreases the effectiveness of the joint.

It is, therefore, one of the objects of this invention to provide an improved expansion joint member in which the possibility of the bituminous material oozing from the upper and lower edges is eliminated.

A more specific object of this invention is to provide an expansion joint member which consists of a single continuous length of saturated fabric which has been wound into oval or cylindrical form and then flattened to form a product composed of a plurality of layers, which is, nevertheless, closed at both the top and bottom.

With the above and other objects in view, the invention consists of the improved expansion joint member and method of forming the same, and all its parts and combinations, as set forth in the claims, and all equivalents thereof.

In the accompanying drawing, in which the same reference numerals designate the same parts in all of the views:

Fig. 1 is a perspective view showing the expansion joint material wound on a roller;

Fig. 2 is a similar view showing the roller removed;

Fig. 3 is a perspective view showing the completed flat expansion joint member;

Figs. 4, 5 and 6 are views similar to Figs. 1, 2 and 3 showing the manner of forming the expansion joint member with an oval form;

Fig. 7 is a modified form of expansion joint member; and

Fig. 8 is a sectional view of the material used in the expansion joint.

Referring to the drawing, the numeral 10 designates the fabric base, preferably felt, of the expansion joint material, and the numeral 11 the bituminous coating which is preferably asphalt. In manufacturing the expansion joint, a continuous strip 12 of the above described material is wound in cylindrical form upon a roller 13 as shown in Fig. 1, or in oval form upon an oval-shaped member 14 as shown in Fig. 4. Next, the form over which the strip has been wound is withdrawn, as illustrated in Figs. 2 and 5, and the material is then flattened or compressed to the shape shown in Figs. 3 and 6.

To produce the modified form of expansion joint member shown in Fig. 7, the same procedure as above described is carried out, except that in compressing the roll, more pressure is directed upon one edge than upon the opposite edge to produce the wedge-shaped finished product shown.

The finished sections shown in Figs. 3, 6 and 7 may be made of any desired length and in use they are inserted in the transverse spaces between pavement sections, with the closed portions forming upper and lower edges. Due to the flexibility of the members, they will permit the pavement sections to expand in warm weather without danger of the road surface buckling. Due to the fact that the expansion joint members are formed of a continuous strip wound in a roll and flattened to form two closed edges, there will be no oozing of the bituminous coating from the upper and lower edges of the members.

From the foregoing description, it may readily be seen that an expansion joint mem-

ber has been produced which is simple in construction, effective in use, and well adapted for the purpose described.

What I claim is:

- 5 1. An expansion joint member for use in paving comprising a strip of fabric having a coating of material which has the characteristic of oozing under the influence of heat and pressure, said joint member being the tu-
- 10 bular wound and flattened formation of said strip, the coating being on the inner side of the fabric and the closed edges of the member preventing loss of coating material from said edges.
- 15 2. An expansion joint member for use in paving, comprising a fibrous web prepared with a coating of material which has the characteristic of oozing under the influence of heat and pressure, said joint member being
- 20 the wound and shaped formation of said web, and having its outermost transverse ends forming sealed edges to retain the coating material within the structure of said member.
- 25 3. An expansion joint member for use in paving, comprising a composite shaped formation of concentric layers of flexible material prepared with an adhesive coating having the property of oozing under the influence of heat and pressure, said adhesive coating being confined within said structure by the sealed edge of the end of the outermost layer of the member.

35 In testimony whereof I affix my signature.
NORMAN P. HARSHBERGER.
